UNITED STATES PATENT OFFICE.

LOUISE B. HENRY, OF MEADOW, NEBRASKA.

COMBINATION CHAIR AND BABY CRIB.

Application filed August 29, 1923. Serial No. 660,006.

To all whom it may concern:

Be it known that I, LOUISE B. HENRY, a citizen of the United States, residing at Meadow, in the county of Sarpy and State 5 of Nebraska, have invented certain new and useful Improvements in a Combination Chair and Baby Crib, of which the following is a specification.

This invention appertains to furniture and 10 more particularly to that type of furniture which can be used for different purposes.

The primary object of the present invention is to provide an improved combined chair and baby crib or basket which is so 15 constructed, that the same will not only be efficient in use, but will present a pleasing and attractive appearance.

Another prime object of the invention is to provide a combined chair and crib, which 20 can be of the wicker type if so desired, embodying a sliding bed board associated with the seat and side walls for the crib slidably associated with the arms of the chair.

A further prime object of the invention is 25 to provide an improved chair and baby crib of the above character, which will be durable in use, one that will be simple and easy to manufacture and one which can be placed upon the market at a reasonable cost.

30 With these and other objects in view, the invention consists in the novel construction, arrangement and formation of parts, as will be hereinafter more specifically described and claimed, and illustrated in the accompanying drawings, in which drawings:

Figure 1 is a longitudinal section through the improved combined chair and crib showing the same open to form a crib.

Figure 2 is an enlarged fragmentary perspective view of the forward end of the frame of the chair illustrating the means of slidably associating the bed bottom with the chair seat.

Figure 3 is a vertical section through the 45 arm of the chair illustrating the means of slidably associating the sides of the bed therewith.

Figure 4 is a perspective view of the frame 50 of the chair and crib showing the bed or crib bottom pulled out to its extended position.

Figure 5 is a detail perspective view of one of the side members or walls of the crib.

55 Figure 6 is a detail perspective view of

the end wall of the crib, which is adapted to be connected with the side walls of the crib when the device is being used as a crib and with the bottom of the device when the same is to be used as a chair, and

Figure 7 is a detail perspective view illustrating one of the brace rods and associate parts.

Referring to the drawings in detail, wherein similar reference characters designate corresponding parts throughout the several views, the letter A generally indicates the combined chair and baby's crib. As shown, when the device is in its folded position, the same forms a chair of the fireside 65 type and this chair can be made out of wicker or any other desired material. In the drawings the chair is made from wicker and built around a suitable supporting frame, which will be now described. The 70 frame of the improved device consists of front and rear pairs of legs 10 and 11 suitably connected together by longitudinal and transverse brace bars 12 and 13. These legs 75 10 and 11 support in spaced relation to the brace bars 12 and 13 a solid seat bottom 14.

The rear pair of legs are extended above the chair bottom 14 to provide posts 15 for the arms and back of the chair, while the front legs 11 are extended above the chair bottom 80 14 to provide supporting posts 16 for the arms of the chair. The posts 15 and 16 are suitably connected together by longitudinal 85 brace bars 17. The posts 15 and 16 carry laterally extending loops 18 formed of wire 90 or the like, around which the sides or arms of the chair 19 are built. This forms an arm or side of hollow construction, for receiving the sides or walls 20 of the device when the same is extended to form a crib, 95

as will be hereinafter more fully described. As shown the rear ends of the side walls 20 of the crib are provided with hooks 21 for hooking over eyes 22 carried by the post 15, to normally prevent the same from being 100 pulled out of the chair. It is preferred that the sides or walls 20 be also formed of a wicker construction, so as to present an attractive appearance to the eye.

The back of the chair is preferably braced 105 by diagonally extending cross brace bars 23 which are connected as at 24 to the post 15. If the posts 15 do not extend far enough above the seat bottom to form a back of sufficient height, a suitable frame 25 shown 110

in Figure 1 of the drawings can be secured to the bars or posts 15 so as to form a support for the wicker work of the back.

The device can also be braced by diagonally extending cross bottom bars 26 which are arranged in spaced relation to the chair bottom 14 and if desired these bars 26 can form supports for blankets, pillows or the like. As shown the cross bars 26 have their terminals connected to eyes 27 carried by collars 28, which are secured to the legs 10 and 11.

Arranged directly below the chair bottom 14 is the crib bottom 30 which is adapted to form an extension of the chair bottom, when the device is used as a crib. This crib bottom 30 normally rests upon the front supporting bar 13 which carries upstanding headed pins 31. These pins are slidably received in longitudinally extending guideways 32 formed in the bed bottom 30 and it is obvious that this bed bottom can be pulled out from the seat or placed under the seat bottom 14, at the will of the operator. The forward edge of the crib bottom 30 supports depending legs 33 so as to permit the supporting of the crib bottom when the same is moved to its extended position. It has been contemplated of dispensing with the pair of legs 10 and using the pair of legs 33 for forming both the support for the device when the same is to be used as a chair and also a support for the device when the same is to be used as a crib. This however, can be made optional by the manufacturer of the device. As shown the legs 33 carry eyes 34 into which are adapted to be placed hooks 35 carried by an end wall 36, which is also preferably formed of wicker work. When the device is being used as a chair, the hooks 35 are placed in the eyes 34 and this wall 36 forms an ornamental front for the chair and hides the brace bars 26 from view.

When the device is to be used as a baby's crib the hooks 35 are placed in the eyes 37 carried by the forward edges of the sides 20.

If preferred the usual chair cushion 38 and 39 can be used as a mattress for the crib, or an extraneous mattress can be used, if so desired.

Now it is obvious that when the device is to be used as a crib that the legs 33 are grasped by the hands of the operator and pulled outwardly, which will slide the bed bottom 30 from beneath the chair bottom 14 and form an extension thereof. The sides 20 are now grasped by the hands of the operator and lifted so as to disengage the hooks 21 from the eyes 22, after which the

same is pulled forwardly. The sides are then connected together by means of the wall 36.

When the device is set up as a crib, it is obvious that the same will still present a neat and attractive appearance to the eye, which will appeal to the trade.

From the foregoing description, it can be seen that an exceptionally simple and strong combined chair and baby's crib has been provided, which is especially useful in small apartments and the like, where the space is limited.

Changes in details may be made without departing from the spirit or the scope of this invention.

What I claim as new is:

1. A combined chair and crib comprising a frame including front and rear supporting legs, transverse longitudinal braces for the legs, a chair back frame carried by the rear pair of legs, hollow side chair arms associated with the frame, headed guide pins carried by the front transverse brace bar, a chair bottom connected with the legs arranged above the brace bars, a crib bottom slidably associated with the frame and arranged below the chair bottom, guide pins carried by the front transverse brace bar, the crib bottom having longitudinally extending slots formed therein for receiving the pins, supporting legs for the forward end of the crib bottom, side walls slidably associated with the hollow chair arms, and a removable front ornamental piece detachably carried by the front pair of legs for association with the side walls when the same are extended to their operative position.

2. A combined chair and crib comprising front and rear supporting legs, a chair bottom connected with said legs, a chair back, hollow chair arms, a crib bottom slidably carried by the chair bottom and normally arranged below the same, crib side walls slidably mounted in the hollow chair arms adapted to be pulled outwardly of said arms, supporting legs carried by the forward end of the said bottom, and a front piece removably associated with the crib bottom arranged to engage and connect the forward terminals of the crib side walls, when said side walls are pulled outwardly from the hollow chair arms.

In testimony whereof I affix my signature in presence of two witnesses.

LOUISE B. HENRY.
